SUPPORTING APPARATUS

Merle Amidon, Elizabeth, Francis T. Lind, North Plainfield, and Oscar P. Lindberg, Elizabeth, N. J., assignors to Western Electric Company, Incorporated, New York, N. Y., a corporation of New York

Application December 12, 1942, Serial No. 468,852

5 Claims. (Cl. 211—144)

This invention relates to supporting apparatus, and more particularly to a truck for supporting articles during transportation and processing thereof.

It is an object of the present invention to provide a simple and inexpensive apparatus for supporting articles during the processing and handling thereof.

In accordance with one embodiment of the invention, a truck is provided for supporting a plurality of trays during the processing of articles on the trays wherein the truck body has vertically extending posts mounted on it, upon which tray receiving brackets are pivotally mounted whereby trays may be readily placed on the brackets and the brackets may then be swung to position over the body of the truck. The brackets have supports upon them which, when the brackets are moved to an intermediate position, may be utilized for supporting elongated articles and the brackets have associated with them support members for bracing them when they are in position over the body of truck. In addition the brackets have aligned apertures formed in opposed portions thereof for receiving rods, on which articles may be suspended, or for receiving portions of articles directly suspended on the brackets.

A better understanding of the invention may be had by reference to the accompanying drawing, wherein

Fig. 1 is a side elevational view of a truck for supporting articles during spray coating, drying and transportation thereof constituting the preferred embodiment of the present invention;

Fig. 2 is a horizontal sectional view taken substantially along the line 2—2 of Fig. 1 in the direction of the arrows;

Fig. 3 is a fragmentary plan view taken substantially along the line 3—3 of Fig. 1 in the direction of the arrows and showing an elongated article supported on two of the brackets in dot and dash lines;

Fig. 4 is an enlarged fragmentary view, partly in section, showing the construction of a bracket and the method in which the brackets are pivotally attached to the framework of the truck, and

Fig. 5 is an enlarged fragmentary sectional view through a portion of the bracket taken substantially along the line 5—5 of Fig. 4 in the direction of the arrows and showing a tray supported in the brackets.

In the drawing, there is shown a truck 10 comprising a body portion or base 11 fitted with suitable casters or wheels 12 and 13. The base 11

has extending upwardly from it and suitably secured to it a pair of posts 14 and 15. The posts 14 and 15 are made of relatively heavy pipe and are threaded at their upper ends to receive elbows 16 and 17, respectively, into which horizontally extending pipe members 18 and 19 are threaded, respectively. The inner ends of the horizontally extending pipe members 18 and 19 are threaded into a pipe 20, in which there is also threaded a central upright member 21, the lower end of which is suitably attached to the base 11.

Mounted upon the posts 14 and 15 are a plurality of sleeves 22, which are freely rotatable about the posts and which are prevented from slipping down on the posts by means of collars 23 fixed to the posts by means of set screws 24. Thus, the sleeves 22 will be held in spaced relation along the posts 14 and 15 and may be freely rotated with respect to the posts. Each of the sleeves 22 has welded to it, as shown at 25 (Fig. 4), a U-shaped channel member 26 constituting a bracket for receiving trays 27 shown in dot and dash lines in Fig. 4. The U-shaped channel member 26 is fixed to the sleeve 22 at the midpoint of its base and the leg portions of the U are adapted to receive angle members 28 which comprise the framework of the trays 27.

In accordance with the preferred embodiment of the invention, the posts 14 and 15 and the horizontally disposed members 18 and 19 are relatively heavy pipes as pointed out hereinbefore as is the upright member 21 and, when rigidly held in the position shown in Fig. 1, will support the U-shaped channel members 26 comprising the tray supporting brackets when the brackets are swung to either the position shown at 29 or 30 in Fig. 2. When the channel members 26 are swung into position shown at 29, trays 27 may be loaded in them and articles supported on the trays may be coated and after the articles are coated, the tray and the channel member 26 may be swung to the position shown at 30 (Fig. 2) for transportation to a drying oven or other destination.

The central upright member 21 has mounted on it a plurality of U-shaped members 31, which are fixed to sleeves 32 freely rotatable about the post 21 and held in position on the post by collars 33. This construction is quite similar to the construction provided on the outer or end posts and the members 31 may be swung to the position shown in Fig. 2 to constitute a support for the inner ends of the trays 27 during the transportation of the trays.

Each of the U-shaped channel members 26 has suitably fixed to its upper surface a bar 35, which is rectangular in cross section, as shown in Fig. 5, and which may be fixed on the channel member 26 by welding it at 36. This bar, which is provided with a knife edge at its upper surface when it is positioned on the channel member 26, may be utilized to support elongated members 37, as shown in Figs. 1 and 3, the channel members 26 being swung to an intermediate position to provide a four-point support for the elongated member 37 during the coating and transportation thereof.

The legs of the U-shaped members 26 have a plurality of apertures 41 formed in them as shown in Figs. 1, 4 and 5 for receiving rods 42 on which parts may be suspended during the coating and transportation thereof.

Thus, the truck made in accordance with the present invention is capable for use for handling various sizes and shapes of parts to be processed, the trays 27 being provided with a suitable mesh screen 40 for holding parts of irregular shapes, the bars 35 being provided for holding elongated articles and the rods 42 being provided for supporting parts which it is desired to suspend in some manner during the processing thereof.

What is claimed is:

1. A supporting apparatus comprising upright posts, and tray receiving frames pivotally mounted on said upright posts, said tray receiving frames comprising channel elements of U-shaped configuration to receive trays between the flanges thereof and said channel elements being provided with knife edged bars on the upper flange thereof for supporting elongated articles.

2. A supporting apparatus comprising a base member, upright posts mounted on said base

member, tray receiving members pivotally mounted on said upright posts and movable to and from position above said base member, a centrally positioned upright member mounted on the base, and means on said centrally positioned upright member to support the inner ends of trays when the members are in position above the base member.

3. In a supporting apparatus, a wheeled base, 10 end posts mounted on the ends of said base, a central upright mounted on the base in alignment with the end posts, tray receiving members on said end posts, tray supporting members on said centrally positioned upright, and means for 15 supporting said members for rotation on their respective upright and posts.

4. In a supporting apparatus, a wheeled base, upright posts mounted on the ends of said base, a central upright mounted on the base in alignment 20 with the upright posts, tray receiving members on said upright posts, tray supporting members on said centrally positioned upright, means for supporting said members for rotation on their respective posts and upright, and means extending between the posts and upright at their upper ends for uniting them in a rigid frame.

5. In a supporting apparatus, a base member, upright posts extending from said base member, a plurality of sleeves rotatably mounted in 30 spaced relation on said upright posts, a U-shaped member individual to each sleeve and having the base thereof fixed to the sleeve, a series of rod receiving bearing surfaces in the legs of each U-shaped member, and rods insertable in the rod 35 receiving bearing surfaces for supporting articles.
